UNITED STATES PATENT OFFICE.

PHILIP E. HENNINGER, OF PITTSBURGH, PENNSYLVANIA, ASSIGNOR TO WESTINGHOUSE ELECTRIC & MANUFACTURING COMPANY, A CORPORATION OF PENNSYLVANIA.

ARMATURE-BANDING MACHINE.

Application filed November 10, 1922. Serial No. 600,179.

To all whom it may concern:

Be it known that I, PHILIP E. HENNINGER, a citizen of the United States, and a resident of Pittsburgh, in the county of 5 Allegheny and State of Pennsylvania, have invented a new and useful Improvement in Armature-Banding Machines, of which the following is a specification.

My invention relates to banding machines, more especially to machines adapted 10 to band armatures for dynamo-electric machines and maintain a uniform tension on the banding material.

It is among the objects of this invention 15 to provide a banding device which shall be capable of banding armatures or like objects in an expeditious and uniform manner, which shall be of simple and inexpensive construction, and which shall be 20 automatic in its control of means for providing proper tension and feeding of the banding material.

My present device comprises a stationary support or bed adapted to rotatably support 25 an armature to be banded and provided with a feeding device which assures a rate of feeding the banding material equivalent to the peripheral speed of the armature. For this purpose I provide a 30 guide-wheel which is directly connected or secured to the spindle by which the object to be banded is rotated and the size of this guide-wheel is the same as the surface to be banded. The guide-wheels may readily 35 be attached to the driving spindle or any suitable part of the machine and may be available in sets corresponding to the change gears commonly employed on machine tools.

40 In the accompanying drawing constituting a part hereof and in which like reference characters designate like parts,

Fig. 1 is a side elevational view of a banding machine embodying the principles of 45 my invention, and

Fig. 2 is an end elevational view thereof.

The device consists of a stationary support or bed plate 1 mounted on suitable pedestals 2 and provided with a head-stock

50 3 having a driving spindle 4 journaled therein which is adapted to be actuated by a suitable driving mechanism (not shown). The head-stock 3 is provided with a face plate 5 and a center 6 on which a rotor 7, such as an armature, is mounted for rota-

tive movement. The other end of the rotor 7 may be supported by a tail-stock (not shown) having a center to engage the recess 8. A plurality of guide rolls 9 are mounted upon the bed plate 1 by means of 60 suitable brackets 10, and a sheave 11 is pivotally mounted on the end of a piston 12, which is mounted in a cylinder 13 secured underneath the bed plate 1. The cylinder 13 is connected, by suitable conduits 14, 65 provided with a gauge 15 and a plurality of valves 16, to a suitable source of liquid pressure, such as air, water or oil by which the piston 12 is actuated.

A feed wheel 18 having a straight or 70 tapered groove or face 19, which is of the same circumference or diameter as the armature 7, is mounted on the spindle 4 by securing it to the face plate 5 in any suitable manner, as by bolts 20.

75 A suitable banding material, such as a wire 22, is taken from a supply reel (not shown) which may be mounted on the bed plate 1 in the plane of the feed wheel 18 upon which several turns are wound and 80 from which it is extended around the guide wheels 9, the sheave wheel 11 mounted on the piston 12, and thence to the armature on which it is wound.

The feed wheel 18 functions to feed the 85 wire 22 at the same rate of speed at which it is wound around the armature 7, inasmuch as both the wheel 18 and the armature 7 are mounted on a common spindle and are of the same diameter. The piston 12, 90 upon which the wire is supported by passing around the sheave wheel 11, functions to provide a uniform tension on the banding material by means of a uniform pressure exerted on the piston which is controllable by 95 means of the pressure gauge 15 and the valve 16. The conical shape of the groove 19 in the feed wheel 18 and the several turns of wire wound therein provides a gripping action and is instrumental in effecting an 100 initial tension on the wire between the source of supply and the piston 12, respectively.

105 It is evident from the above description of my invention that it constitutes a simple and efficient means for banding armatures or other light rotating bodies and that such banding is accomplished in a simple and expeditious manner. The feed wheel 18 is considered a decided improve- 110

ment over the prior art which did not provide for the feeding of the wire independently of the rotor or body upon which it was wound.

Although I have described a specific embodiment of my invention, it will be obvious to those skilled in the art that various modifications may be made in the details of construction. For instance, the feed wheel need not be mounted on the main drive spindle of the banding machine but may be journaled on an independent shaft geared to or otherwise driven by the driving spindle or an independent source of power. The liquid-pressure-actuated tension member may be automatically controlled by suitable check valves or other means well known in the art, and the general design and construction may be modified to accommodate some particular condition of use. These and other changes may be made without departing from the principles herein set forth.

I claim as my invention:

- 28 1. A banding machine comprising a base adapted to rotatably support an object to be banded, feeding means adapted to feed the banding material at a speed corresponding to the peripheral speed of the rotating object and means for regulating the tension of said material.
- 29 2. A banding machine comprising a base adapted to rotatably support an object to be banded, feeding means adjacent to said object adapted to feed the banding material at a speed corresponding to the peripheral speed of the rotating object and means for regulating the tension of said material.
- 30 3. A banding machine comprising a base adapted to rotatably support an object to be banded, feeding means adjacent to said object adapted to feed the banding material at a speed corresponding to the peripheral speed of the rotating object and means for automatically regulating the tension of said material.
- 31 4. A banding machine comprising a base

adapted to rotatably support an object to be banded, means for feeding the banding material from a supply reel to said object at a speed corresponding to the peripheral speed thereof and means for providing uniform tension on said banding material.

5. A banding machine comprising a base adapted to rotatably support an object to be banded, means for feeding the banding material from a supply reel to said object at a speed corresponding to the peripheral speed thereof and means for providing uniform tension on said banding material, said feeding means comprising a drum having a grooved periphery of the size of the object to be banded and said tension means comprising a fluid-actuated-piston mechanism.

6. A banding machine comprising a base adapted to rotatably support an object to be banded, means for feeding the banding material from a supply reel to said object at a speed corresponding to the peripheral speed thereof and means for providing uniform tension on said banding material, said feeding means comprising a drum having a grooved periphery of the size of the object to be banded which is direct-connected to the rotating object and said tension means comprising a fluid-actuated-piston mechanism.

7. A banding machine comprising a base adapted to rotatably support an object to be banded, means for feeding the banding material from a supply reel to said object at a speed corresponding to the peripheral speed thereof and means for providing uniform tension on said banding material, said feeding means comprising a drum having a grooved periphery of the size of the object to be banded which is mounted on the same spindle as the rotating member and said tension means comprising a fluid-actuated-piston mechanism.

In testimony whereof, I have hereunto subscribed my name this 3rd day of November 1922.

PHILIP E. HENNINGER.
